Diagram of a mechanical device labeled "Fig. 1" with various numbered parts. The device has a rectangular base with a central slot. A vertical rod extends from the top of the base. A horizontal rod is attached to the top of the vertical rod. A curved arm extends from the side of the base. Numbered callouts point to specific parts: "56" points to the top of the vertical rod; "57" points to the top of the horizontal rod; "58" points to the top of the curved arm; "59" points to the side of the base; and "60" points to the side of the vertical rod.

UNITED STATES PATENT OFFICE.

EMERSON C. EACHEL, OF MONTCLAIR, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,259,497.

Specification of Letters Patent. Patented Mar. 19, 1918.

Application filed July 3, 1913. Serial No. 777,137.

To all whom it may concern:

Be it known that I, EMERSON C. EACHEL, a citizen of the United States, residing in Montclair, in the county of Essex and State 5 of New Jersey, have invented certain new and useful Improvements in Combined Type-Writing and Computing Machines, of which the following is a specification.

This invention relates to computing machines of the kind in which figures are printed as the numeral keys are struck, and the invention relates more particularly to means for printing the numbers on the work-sheet without computing the same.

15 According to the present invention, the numeral keys may be operated to print the figures and compute the number in the ordinary way; but at any time a special key may be depressed which will disconnect the computing mechanism from the keys, so that the latter will print without computing; but this 20 printing will not be done with the same types that are used when computing is being done. By means of said special key, the computing mechanism will be disconnected or silenced, and the numeral keys, if 25 operated, will print the number on the work-sheet in types which are essentially different from the types that are used at the computing operation.

This invention is shown applied to an Underwood-Hanson combined typewriting and computing machine, in which, at the operation of the numeral keys, index pins are set 35 up one after another; and at the conclusion of the writing of the number, a general operator is brought into use to carry into the adding wheels the number which has been so set up on the index pins.

40 This index-pin controlling mechanism includes a dog which is mounted on the paper carriage of the typewriter, for selecting the denomination of the index-pin; and upon depressing a special key, said dog is silenced, 45 so that the numeral keys of the typewriter may be operated without setting any index pins, or performing any computation.

The same dog-silencing key also shifts the case-shift mechanism of the typewriter, so 50 as to put the computing types out of use and bring into play the set of special types which are distinctive therefrom. Hence at any time a number may be written on the work-sheet without computing, even though

the carriage is in the computing zone; and 55 a further advantage is gained, that the number which is so written without computing, appears upon the work-sheet in a distinctive type from numbers which are computed; so that danger of error is avoided.

60 Preferably each of the figure type bars on the Underwood machine is made with a large-faced figure type and a small-faced figure type; the large-faced figure type being in the lower-case set, so as to be used 65 when computing; while upon depressing the shift key the platen is shifted up to bring into use the small types, and at the same time the computing mechanism is temporarily disconnected from the computing 70 keys.

In the accompanying drawings,

75 Figure 1 is a perspective view of a fragment of a type bar on which is mounted a double type.

Fig. 2 is a diagrammatic view to show the operation of the case-shift mechanism and the computing disconnection mechanism.

Fig. 3 is a sectional side elevation of a combined typewriting and computing machine of the Underwood-Hanson type, showing the parts in normal positions, and showing in dotted lines a computing type in printing position.

Fig. 4 shows the types on the ends of the 85 type bars.

Fig. 5 shows a plan of the numeral keys which operate the types seen at Fig. 4, said keys being unprovided with extra characters, contrary to the usual custom in single-shift 90 typewriting machines.

The typewriting machine comprises alphabet keys 1 and numeral keys 2, all of the keys connected to levers 3, which, by means of bell cranks 4, swing type-bars 5 up 95 against a platen 6. The platen is mounted on a carriage 7 which has a letter-feeding rack 8 connected by means of a pinion 9 with an escapement wheel 10, the latter co-operating with feeding dogs 11 controlled 100 by a universal bar 12 operated by the type-bars, whereby the carriage is fed step by step as the writing proceeds. Each numeral key 2 has a stem 13 which depresses an arm 14, of which there is one for each 105 key, as usual in the Hanson writing machine; these arms mounted on rock shafts 15 which carry arms 16 pivoted to links 17,

each of the latter forming a part of a linkage, the linkages being designated generally as 18, and being in position to depress index pins 19. These index pins are normally 5 beyond the reach of the key-operated linkages 18, but upon the typewriter carriage 7 is a dog 20 which one by one lifts levers 21 pivoted at 22 to depress links 23 and rock levers 24, which, by means of the usual 10 transposition device 25, lift the rear ends of bars 26 by which said index pins are carried, whereby the index pins are brought into reach of the key-operated linkages 18. These bars 26 are raised one after another, 15 thus bringing each file of index pins successively within reach of the key-operated linkages 18, whereby the operation of the numeral keys 2 to print causes the corresponding number to be set up upon the index pins, of which there are usually eighty- 20 one, there being usually nine of the bars 26.

After the number is written, and the corresponding pins are accordingly set, a general operator is brought into use. This general operator comprises a cross bar 28 which immediately underlies the index pin bars 26 so as to carry forward all of the bars 26 on which pins have been set by the keys 2; and by means of racks 29 on the forward ends of these bars 20, pinions 30 are rotated accordingly, and the number wheels 31 are turned with them, said bars 27 forming part of the general operator. The general operator is usually driven by means of a rock shaft 32 having segments 33, which, by means of pinions 34, control racks 35 on slide bars 27 at the opposite sides of the machine. Thus the writing of the numbers in a column may proceed line by line, and 40 after each number is written the adding wheels 31 may be turned a corresponding amount.

Sometimes in beginning a column it is desired to write a number without having it carried into the adding wheels 31; and in that case the operative depresses a special key 36, which is mounted on the forward end of a lever 37, pivoted upon the same rod 38 as the levers 3 and having a similar 45 turning spring 39, and also having an up-standing rock arm 40 which rocks forwardly and swings up an arm 41 depending from a rock shaft 42; the latter also having a rearwardly extending arm 43 which carries at 50 its rear end a roll 44, that now runs down along a cam arm 45 depending from a rock shaft 46, and swings said arm forwardly, while an up-standing arm 47, rising from the same rock shaft, is swung rearwardly, 55 and a supporting roll 48 at the top of said arm 47 is withdrawn, so that the mount 49 which is normally supported by said roll 48 and which carries said denomination-selecting dog 20, is allowed to drop, swinging 60 down about a rod 50 which is provided upon

the carriage 7. The positions of the parts at this moment are indicated at Fig. 2, in which it will be seen that the dog 20 can no longer operate any of the denomination jacks or levers 21. The mount 49, as usual, 70 carries a roll 51 which rests upon the supporting roll 48; this roll 51 being beveled to facilitate the subsequent return of the parts to normal position.

When the silencing key 36 is held down, 75 the operative may depress the numeral keys 2; at this time the types 52 will be out of use, for the reason that the arm 41 is connected to a shift rail 53 to lift the same, together with a roll 54 running thereon, and 80 connected to a shift frame 55 on the paper carriage 7, whereby said shift frame is lifted, together with the platen 6, so high, as at Fig. 2, that the large types 52 cannot print, but the small figure types 56 are caused to 85 strike the platen, thus making very much smaller characters than those which are written at the time that the adder-silencing and case-shift key 36 is in normal Fig. 1 position.

Hence the operation of printing numbers 90 without computing is facilitated by a very simple and inexpensive means, and the further advantage is gained that the writing shows for itself that the number was not carried into the computing wheels 31. 95

Variations may be resorted to within the scope of the invention, and portions of the improvements may be used without others.

Having thus described my invention, I 100 claim:

1. In a combined typewriting and computing machine, the combination of a single set of numeral keys; two sets of alternatively-usable numeral types directly actuated by said keys and arranged in pairs, one 105 pair individual to each numeral key to be operated thereby, both types of each pair being constructed to always write the same numeral at the operation of the corresponding key, but the impression written by one 110 type of the pair having a distinctly different appearance from that written by the other type of the pair, whereby the actual appearance of each number itself as written on the work-sheet will be self-indicative 115 of the particular set of types by which it was written, all of the types in all of the pairs being mounted to strike at a single printing point; computing mechanism operatively associated with said keys, to be 120 controlled thereby, solely when one definite set of types is operated by said keys; and means for simultaneously causing the other set of types to strike at the operation of said keys and silencing said computing mechanism. 125

2. In a combined typewriting and computing machine, the combination, with a carriage, and computing mechanism having a part controlled by said carriage; of 130

a single set of numeral keys controlling the travel of said carriage and operatively associated with said computing mechanism; two sets of alternatively-usable numeral types 5 directly actuatable by said keys to strike at a single printing point and arranged in pairs, one pair individual to each numeral key, both types of each pair being formed for always 10 writing the same numeral at the operation of the corresponding key, but the impression written by one type of the pair having a distinctly different appearance from that written by the other type of the pair, whereby the actual appearance 15 of each number itself as written on the work-sheet will be self-indicative of the particular set of types by which it was written, one of said sets of numeral types being normally ineffective at the type strokes; and a shift key connected to render effective at the key strokes the said ineffective set of numeral types and to simultaneously silence the computing mechanism. 20

3. In a combined typewriting and computing machine, the combination of a single set of numeral keys, operable one after another to typewrite, two sets of alternatively-effective numeral types connected to said keys to be directly actuated thereby,

and all arranged to strike at a single printing point, said types arranged in pairs, one pair individual to each numeral key, both types of each pair being formed for always 30 writing the same numeral at the operation of the corresponding key, but the impression written by one type of the pair having a distinctly different appearance from that written by the other type of the pair, whereby the actual appearance of each numeral itself as written on the work-sheet will be self-indicative of the particular kind or set 35 of types by which it was written, computing mechanism operatively associated with said keys to be controlled thereby at the successive type-striking operations of said keys, while effectively operating one set of 40 said numeral types, means for varying the state of said computing mechanism at the key operations, and means connected with said varying means for bringing into effective operation at the key strokes the other 45 set of said numeral types. 50
